UNITED STATES PATENT OFFICE.

AUGUSTE LOUIS RICORDEL, OF PARIS, FRANCE, ASSIGNOR TO SOCIÉTÉ ANONYME
LA PRÉCISION MODERNE, OF PARIS, FRANCE.

MACHINE-GUN CARRIAGE.

Application filed September 19, 1927, Serial No. 220,594, and in France September 30, 1926.

My invention has for its object a machine gun carriage specially adapted for anti-aircraft firing comprising a stationary basis and a guiding support adapted to rotate 5 round the vertical axis of the basis and bearing in its turn a toothed limb along which may move the front of the cradle of the machine-gun; the rear of this cradle at the rear of the machine-gun is provided with horizontal trunnions rotating in bearings of the guiding support. In this manner the machine gun instead of pivoting, as in the usual carriages, round a horizontal axis disposed substantially at its center of gravity, pivots 10 round its butt-end.

To equilibrate the weight of the gun I use a coil spring housed in the vertical pivot of the carriage and acting on a cam-shaped projection disposed underneath the cradle, 20 this cam being adapted to constantly afford a correct poising of the machine-gun and its cradle, whatever the angle of the former with the vertical.

In view of providing a proper firing for 25 any position of the machine-gun, I use two cooperating cams one of which pivots round a stationary point of the carriage and the other is borne by the axis of that part of the machine-gun which causes the fire to flash.

Moreover my improved carriage may be 30 taken to pieces so that the gunners may carry it easily. In particular, I have imagined an arrangement wherein the correcting device for anti-aircraft firing may be set immediately on the support.

A form of execution of my invention is shown by way of example on appended drawings whereof.

Fig. 1 is a side view of the carriage.

Fig. 2 is a rear view, wherein the guiding support is shown in a somewhat different position with reference to its basis.

Fig. 3 is a diagrammatical plan view of the controlling device for the rotation of the 45 guiding support.

Fig. 4 is a detail diagrammatical view of the site movements of the machine-gun,

Figs. 5, 6, 7, 8, 9 are views of the disconnected parts of the carriage,

50 Fig. 10 is a perspective view of the carriage with the correcting device secured to it.

Fig. 11 is a perspective view of the corrector, in the position used for transportation.

Fig. 12 is a plan view which shows the 55 mounting of the correcting device on the carriage.

Fig. 13 shows diagrammatically how the fire is caused to flash,

Fig. 14 is a rear view of a double carriage,

Fig. 15 is a side view of a modified form of this double carriage.

The carriage comprises a stationary basis with its feet 2 and a guiding support 3 65 adapted to rotate on the basis. In view of this the socket 4 integral with the basis bears a toothed ring 5 (Figs. 1 and 3) meshing with a worm 6 connected through a rod 7 and a set of bevel pinions 8 with a handwheel 9 disposed in front of the gunner. This handwheel and the gunner's seat 11 are borne by the support 3. When the gunner rotates the handwheel, he causes the guide 3 to move with himself round the ring 5. 75

An axial tube 12 is engaged in the socket 4 and 5 and allowed to rotate therein thanks to the interposition of the ball bearings 13. The tube 12 is secured to the vertical limb 14 rotating with the support 3 and provided 80 with teeth meshing with the pinion 15 (Fig. 4) pivotally secured to the cradle 16 of the machine gun 17. This cradle is provided at its rear with trunnions 18 adapted to rotate in the bearings 19 borne by the support 3. 85

The site movements of the machine gun are provided by the movements of the pinion 15 over the limb 14 and are controlled by the handwheel 21 which through the bevel pinions 22 causes the worm 23 engaging the 90 pinion 15 to rotate. Of course any other equivalent means may be used for controlling the pinion 15.

In order to equilibrate the weight of the front part of the machine gun, in the central tube 12 of the support there is disposed a tube 24 closed at its top and urged upwards by a strong coil spring 25. The tube 24 is provided at its top with a recess wherein is disposed a roller 26. A cam-shaped 95 projection 27 secured to the cradle 26 bears on this roller; it is cut in a manner such as

will provide for the equilibrium of the machine gun and its cradle whatever angle it is set at.

The firing (Figs. 1 and 13) is somewhat difficult to ensure properly under all firing angles. A pedal 28 pivotally secured to a part borne by the support 3 is connected pivotally with a rod 29 which in its turn is pivotally secured to a cam 31 pivoting round the stationary point 32. On the other hand, the rotary part which causes the fire to flash and which varies according to the type of machine gun is provided with controlling part 33 which is also cam-shaped. Evidently when the pedal 26 is lowered, the cam 31 is caused to rotate whereby the cam 33 is also rotated and the gun is fired. The cams 31 and 33 are shaped so as to remain always in contact and to provide for the action of cam 31 on cam 33 to cause a sufficient movement of the latter for making the firing of a shot certain. Near the pedal 28 (Fig. 2) are the foot-rests 34 for the gunner.

As the carriage is intended for firing 25 against aircraft, it is generally provided with a correcting device which may be of the type described in the French Patent No. 629,442 filed on May 3, 1926, in the name of "La Précision Moderne". I will describe it 30 only in so far as it is necessary for understanding how it may be set on the carriage. This device is adapted chiefly to take into account, when firing, of the corrections due to the movements of the aircraft and also 35 of the deformations of the path of the shot according to the angle of site used.

This correcting device comprises mainly 40 a cylindrical box 35 (Figs. 1, 2, 10) which remains constantly vertical under the action of the arm 37 secured to it and pivotally 45 borne at 39 by the cradle 16. To the arm 37 is pivotally secured at 41 a rod 36 pivoting round a point 38 (Fig. 1) of an extension of the limb 14. The four points 39, 41, 38 and 18 form a parallelogram motion which 50 keeps the cylindrical box 35 constantly vertical. Inside the box a suitable block 42 is allowed to rotate and bears an arrow 43 which a gunner directs parallel to the movement of the aircraft. Under the box 35 and 55 eccentrically with reference thereto projects a rod 44 connected with the arrow and ending with a cardan suspension 45. The position of the rod 44 and consequently of the cardan suspension is determined as to height and eccentricity by suitable control gears, according to the corrections to be brought to the sighting. The cardan 45 is connected with the rod 46 pivotally secured at 47 to a 60 rod 50 adapted to rotate in a sleeve 51 stationary with reference to the rod 36. The end of the rod 46 is pivotally secured to the rod 48 pivotally secured on the other hand to the plate bearing the collimator 49 and 65 pivotally secured to the rod 50 passing

through the sleeve 51. Evidently the collimator 49 will be set parallel to rod 46 and the arm 46 swivelling at 45 and moving with rod 44 will take any position with reference to the arm 36 parallel to the gun. Thereby the collimator may make with the axis of the gun any desired angle of correction.

It is very important that the above described carriage may be taken to pieces into parts small enough to be carried by a gunner or on a mule's back; Figs. 5 to 9 show these parts for the form of execution described: the basis 1 together with the rotating part 3 of the support (Fig. 6); the feet 2 which may be secured together (Fig. 8) and are 70 adapted to engage the recesses 52 provided in the basis 1; the limb 14 with the tube 12 (Fig. 5), the pedal 28 with the foot rests 34 and the pedal holder 53 passing over the spindle 54 borne by the limb (Fig. 5), the seat 11 to be attached to the rotating support 3 (Fig. 9).

It is essential that the breakable parts such as the correcting device with its collimator should for transportation, be contained in a box and be adapted to be instantaneously set in a correct manner on the carriage. In view of this, the whole removable correcting device comprises (Fig. 11) the following parts: the cylindrical box 35 with its arrows 43, the cardan arrangement 44, 45, 46, the rod 48, the collimator 49, the sleeve 51 secured to a U-shaped iron 55 adapted to be borne by the rod 36 which is slotted (see Fig. 10) for receiving the bolting lever 57 controlled by a handle 58. On the other hand a projection 59 allows the assembling of rods 36 and 37 (Fig. 12) and the U shaped iron 55 is provided at its end pivoting with reference to the box 35 with a 90 hollow socket adapted to be set over the projection 59. A lug 62 is secured to box 35 and may engage through its slot 63 a pin 64 borne by the arm 37 and provided with a winged nut 70.

The whole correcting device shown on Fig. 11 is very easy to set on the carriage. It is sufficient to dispose the socket 61 over the projection 59 and the lug 62 is hooked on the pin 64, the nut 70 being then fastened down. The part 55 is then set along the rod 36 and the bolt 57 engaging the slot 56, the handle 58 is turned so as to secure the parts together.

Fig. 14 shows a carriage as it is used with 120 two guns fed through the top. These two guns are borne by two cradles 69, 71 disposed on either side of a single limb 72, a single device ensuring the rotation of the two guns. If on the contrary the guns are 125 fed through the side with strips of cartridges they may be shifted as to height so as to facilitate the feeding as shown on Fig. 15. In view of this the gun 74 pivots round the bearings shown diagrammatically 130

at 75. It is kept parallel with the gun 73 through the rod 76 forming a parallelogram with the line joining two points on the pivoting axis of the two guns.

5. More than two guns may be borne by my improved carriage through a multiple cradle disposed on the side of the limb.

What I claim is:

1. A machine gun carriage chiefly for anti aircraft firing comprising a stationary basis, a rotatable guiding support borne by said basis, fixed bearings on said support, a cradle to which the machine gun is rigidly connected so that its rear end is maintained adjacent trunnions rigid with the rear end of the cradle and supported by the bearings of the support, a seat for the gunner borne by the supports, devices borne by the support to control the direction and site movements of the gun, means for controlling the fire, a device equilibrating the gun and cradle for all positions in site, a limb secured in a plane parallel to that in which the axis of the gun is allowed to be pivoted, a correcting device borne on rods forming with the limb on the cradle a parallelogram motion, and means to secure removable to each other the different members of said gun carriage.

30. 2. In a machine gun carriage as claimed in claim 1 an equilibrating spring disposed inside and round the axis of rotation of the support, a projecting cam on the underside of the cradle and submitted to the action of the spring, the cam having a shape such as will provide for the equilibrium of the gun and cradle for all positions in site.

35. 3. In a machine gun carriage as claimed in claim 1 a tube secured under the support

and disposed round its axis of rotation, a second tube closed at its top slidingly disposed inside the first tube, a spring urging the second tube upwards, a roller inside the first tube above the second tube, a projecting cam on the underside of the cradle and bearing on the roller, the cam having a shape such as will provide for the equilibrium of the gun and cradle for all positions in site.

4. In a machine gun carriage as claimed in claim 1, a cam pivoting round a point of the support, a pedal borne by the support and actuating said cam, a part on the cradle adapted to control the fire of the gun, a second cam adapted to actuate said part and controlled by the first cam for all positions of the cradle in site.

5. In a machine gun as claimed in claim 1, a correcting device, a socket borne thereby, a rod pivotally secured to the limb at one end, a second rod pivotally secured to the first rod and to the cradle, a stud borne by the two rods at their connection and engaging the socket on the correcting device, a notched lug borne by the correcting device, a stud on one of the rods engaging the notch in the lug, an arm pivotally secured to the correcting device and a bolt for securing said arm on the other rod.

6. In a machine gun as claimed in claim 1, a second cradle disposed above the first one in the same vertical plane, means to secure invariably both cradles to each other, and a second machine gun borne by said second cradle.

In testimony whereof I affix my signature.

AUGUSTE LOUIS RICORDEL.
